UNITED STATES PATENT OFFICE.

JOHN H. GILL, OF YONKERS, NEW YORK.

SPARK-PLUG.

1,273,476.

Specification of Letters Patent.

Patented July 23, 1918.

Application filed August 2, 1916. Serial No. 112,664.

To all whom it may concern:

Be it known that I, JOHN H. GILL, a citizen of the United States, residing at No. 326 McLean avenue, Yonkers, in the county of 5 Westchester and State of New York, have invented certain new and useful Improvements in Spark-Plugs, of which the following is a specification.

My invention relates to improvements in 10 spark plugs and my aim is to provide a superior article having a number of practical advantages. The principal object of the invention is to provide a spark plug wherein the sparking area will be very largely diffused, so as thereby to result in more efficient 15 and certain ignition of the explosive mixture. A further object is to provide a spark plug which to a very large extent will be self-cleaning and will automatically prevent 20 the deposition of carbon, soot and oil between the electrodes to thereby impair the effective operation of the device. The improved spark plug is very sturdy and durable in construction.

25 In order that the invention may be better understood attention is directed to the accompanying drawing forming a part of this application, and in which—

Figure 1 is a side elevation partly in section of a spark plug embodying my present 30 improvements;

Fig. 2 a bottom view of the same;

Fig. 3 a side elevation of the movable electrode, and

35 Fig. 4 a bottom view showing a modified form of movable electrode.

In these views corresponding parts are represented by the same reference numerals.

The porcelain 1, cylindrical casing 2 and 40 center rod 3 are of any usual or well known construction. Mounted on the center rod 3, and preferably so as to turn loosely thereon, is an electrode 4 which in practice is located usually slightly within the rim of the cylindrical casing 2. The distance between the periphery of the electrode 4 and the interior of the casing 2 is so selected as to give the proper spark. The electrode 4 is provided with a series of teeth or points so as 45 thereby to produce a multiplicity of sparks between the same and the interior of the casing 2. In Figs. 1, 2 and 3, I show the electrode as being formed with a series of inclined vanes 5 like a minute pinwheel, and 50 in Fig. 4 I show as a modification an electrode in the form of a five-pointed star. Its

shape may however be very widely modified, as will be obvious to those skilled in the art. In actual practice I prefer to mount the electrode so that it may rotate freely on and 60 with respect to the center rod 3 and I therefore prefer to make use of a washer 6 between the electrode and the lower end of the porcelain. The metal of the center rod may be upset at its end as shown at 7 so as to 65 form a lower bearing for the electrode. In actual practice the natural vibrations of the engine and the explosions taking place within the cylinder, will cause the electrode 4 to constantly shift its position, so that the 70 sparks between the same and the casing 2 will be distributed in a concentric path extending around the interior of said casing, and thus the path in which the sparks are formed will be always kept clean and free 75 from any deposition of carbon, soot and oil. By making the electrode 4 with a series of wings or vanes as shown in Figs. 1, 2 and 3, the successive compressions and explosions within the cylinder will very materially assist 80 in the rotary effect, and therefore in some respects this is the preferred form. It will be understood, of course, that the electrode 3 is to be made of some very hard metal or conducting material, preferably an alloy 85 of steel and platinum, or it may be made of steel with platinum tips.

It will be further understood that while I refer to the element 1 as a porcelain, it may be made of any other insulating material, 90 such as mica, and in the following claims it will be understood that the expression porcelain applies generically to any suitable insulating material for the purpose.

Having now described my invention, what 95 I claim as new therein and desire to secure by Letters Patent, is:

1. As a new article of manufacture, a spark plug comprising a fixed annular electrode, an insulating body mounted within 100 the annular electrode and rigidly connected thereto, a rod mounted centrally and rigidly within the insulating body and a disk-like electrode mounted to rotate freely at the lower end of said rod within the annular 105 electrode, said disk-like electrode presenting a multiplicity of points whereby sparking takes place between said points and the inner wall of the annular electrode, substantially as and for the purposes set forth. 110

2. As a new article of manufacture, a spark plug comprising a fixed annular elec-

trode, an insulating body mounted within the annular electrode and rigidly connected thereto, a rod mounted centrally and rigidly within the insulating body and a disk-like electrode mounted to rotate freely at the lower end of said rod within the annular electrode and formed with a series of radially inclined fan blades which present a multiplicity of points whereby sparking

will take place between said points and the inner wall of the annular electrode, substantially as and for the purposes set forth.

This specification signed and witnessed this first day of August, 1916.

JOHN H. GILL.
